UNITED STATES PATENT OFFICE.

WILLIAM E. BERTRAM, OF BROOKLYN, NEW YORK, ASSIGNOR TO INTERNATIONAL TYPESETTING MACHINE COMPANY, OF NEW YORK, N. Y., A CORPORATION OF NEW YORK.

LINOTYPE MACHINE

1,124,101.

Specification of Letters Patent. Patented Jan. 5, 1915.

Application filed November 23, 1911. Serial No. 661,937.

To all whom it may concern:

Be it known that I, WILLIAM E. BERTRAM, a citizen of the United States, residing at Brooklyn, in the county of Kings and State of New York, have invented new and useful 5 Improvements in Linotype-Machines, of which the following is a specification.

The present invention relates to improvements in linotype machines and more especially to the mechanism for ejecting the slugs from the mold after each casting operation, and the object of this invention is to provide simple and improved means for operatively connecting ejector blades of different sizes to the ejector slide whereby blades corresponding to molds of different sizes or to the different adjustments of a mold may be quickly and easily applied and removed relatively to the ejector slide, there- 10 by facilitating the operation of interchanging these blades and adjusting the machine to produce slugs of different lengths and thicknesses.

To these and other ends, the invention 25 consists in certain improvements, and combinations and arrangements of parts, all as will be hereinafter more fully described, the novel features being pointed out particularly in the claims at the end of the specification.

30 In the accompanying drawing:—Figure 1 is a side elevation of an ejector slide and an ejector blade provided with means embodying the present invention for detachably connecting the slide to the different blades;

35 Fig. 2 represents a section on the line 2—2 of Fig. 1; Fig. 3 is a perspective view of an ejector blade; and Fig. 4 is a perspective view of the locking pawls, the same being removed from the ejector slide.

40 Similar parts are designated by the same reference characters in the several views.

In the operation of linotype machines, the slugs are cast in a mold or molds the size of which is varied in order that the machine 45 may produce slugs of different lengths and thicknesses. In adjusting or altering the machine to enable it to cast slugs of different sizes, it is necessary to employ an ejector blade which corresponds to the size of the mold and in practice a set of blades of different sizes is provided in order 50 that the slugs of corresponding sizes may be properly ejected from the mold in which they are cast.

55 The present invention provides simple and

improved means whereby the different ejector blades may be quickly and easily interchanged with respect to the ejector slide, thereby minimizing the delay incident to altering or adjusting the machine for the 60 production of slugs of different sizes.

The preferred embodiment of the invention is shown in the accompanying drawing, 1 designating the usual ejector which reciprocates in the mold slide and is operated as usual by a pitman one end of which is engaged in the socket 2 of the ejector slide. The constructions of the mold slide and the means for operating the ejector slide are well known in the art and, hence, 65 they are not illustrated in the drawing. That part of the ejector slide to which the different ejector blades are to be attached is preferably undercut to form a transverse recess or seat 3 which is adapted to receive 70 a correspondingly shaped part of each ejector blade. Fig. 3 shows one of the ejector blades 4 and the rear end of this blade is formed with an extension 5 which corresponds in thickness to the depth of the 75 seat or groove 3 of the ejector slide and such extension of the blade is adapted to enter and fit said seat or groove in such a manner that the rear face of the ejector slide and the rear face of the blade will occupy the same 80 plane. The body of the blade 4 is of uniform thickness throughout its extent although the extensions 5 of the larger 85 blades of the set will be of reduced thickness as compared with the thickness of the 90 body of the blade. It will be understood that a set of ejector blades of appropriate sizes are intended to be used but the extensions or attaching portions 5 of the different 95 blades of the set will be of the same thickness whereby they may properly fit the seat or groove 3 of the ejector slide. Each of 100 these blades when used operates through its corresponding mold to eject the slug therefrom, in the well known manner.

The means provided by the present invention for detachably connecting the different ejector blades to the ejector slide embodies a suitable number of hooked pawls which are adapted to engage a corresponding number of appropriately shaped recesses formed in the attaching portions of the ejector blades. In the present instance a pair of pawls 6 are used, these pawls being 105 turnable on pivots 7 secured to the ejector 110

slide and the pawls operate in suitable recesses 8 which are formed in the rear face of the ejector slide.

The free or operative ends of the pawls project into the groove or seat 3 of the slide and are provided with laterally turned locking projections 9, these locking projections on the different pawls pointing in the same direction and they extend in the plane of movement of the pawls. The attaching portion or extension 5 of each ejector blade is formed with a corresponding number of recesses or sockets which coöperate with the operative ends of the pawls. As the ejector slide 15 in the present instance is provided with a pair of locking pawls, the operative portion or extension of the ejector blade is also provided with a pair of recesses or sockets 10 which, when the blade is in operative relation to the slide, receive the operative ends of the respective pawls. The recesses or sockets 10 of the blade are formed with notches 11, these notches extending laterally and in the same direction from the recesses 20 or sockets and these notches form locking shoulders 12. When the ejector blade is in operative relation to the slide, the locking projections 9 of the pawls engage in the notches 11 of the respective recesses or sockets of the blade and such locking projections on the pawls abut against and interlock with the respective shoulders 12. The recesses or sockets 10 are properly shaped to permit the pawls to rotate about their pivots to engage 25 and disengage the locking projections 9 thereon with respect to the shoulders 12. The movements of the pawls to engage and disengage them with respect to the blade are in a plane parallel to the plane of the blade 30 and although the attaching end or portion of the blade is comparatively thin, the co-operative locking surfaces of the projections 9 of the pawls and the shoulders 12 of the blade are of sufficient area to maintain a firm connection between the blade and slide, and the necessary movements of the pawls 35 to lock and unlock them with respect to the blade are provided for although the parts occupy a very compact relation.

Different means may be provided for operating the pawls to lock and unlock them with respect to the ejector blade. In the present instance the pawls are connected so as to move in unison by a bridge member 13 which is pivotally connected to the pawls and operates in a transverse slot 14 of the slide. An operating handle or lever 15 is provided at the forward side of the ejector slide, it being pivoted to the slide at 16 and it is connected by a pivot pin 17 to the bridge member 13. The free end of this handle or lever is preferably formed with a flexible section 18 and this flexible section bears a dog 19 which is adapted to seat in a notch 20 in the slide to retain the pawls in locked position.

or to engage in a second notch 21 in the slide to retain the pawls in unlocked position, disengagement of the dog 19 from either notch being effected by springing the flexible section 18 of the handle outwardly, the resilience of said section serving to normally retain the dog in engagement with either of these notches. The handle may be readily shifted to simultaneously move the pawls into locking and unlocking positions.

The ejector slide and blade are adapted to reciprocate as usual in the mold slide, the edge 22 of the blade and the edge 23 of the ejector slide toward which the locking projections 9 and the notches 11 are directed being in alinement and coöperating with a guiding wall 24 of the mold slide while the rear faces of the ejector slide and the blade which are in the same plane coöperate with a wall 25 of the mold slide. The ejector blade is therefore prevented from moving either in an edgewise direction or in a flatwise direction to disengage itself from the locking pawls of the ejector slide, the locking and unlocking of the ejector blade being controlled wholly by manipulation of the locking pawls.

I claim as my invention:

1. In a machine of the linotype class, the combination of an ejector slide, an ejector blade, said slide and blade having abutting ends, and a pawl connected to one of said parts, extending across the abutting ends of such parts and having a hook-shaped portion detachably connected to the other part to withdraw the blade upon the return stroke of the slide.

2. In a linotype machine, the combination of an ejector slide, an ejector blade provided with a notched recess open at one end of the blade, and a pawl movably connected to said slide and having a hooked end adapted to extend longitudinally into said recess to coöperate with the notch thereof.

3. In a linotype machine, the combination of an ejector slide, an ejector blade provided with a recess open at one end thereof having a locking shoulder at one side, and a pawl movably connected to said slide and having a hooked end adapted to extend longitudinally into said recess and coöperate with the locking shoulder therein.

4. In a linotype machine, the combination of an ejector slide, an ejector blade having a recess open at the attaching end thereof and having a lateral locking shoulder, and a laterally movable pawl on the slide having a laterally directed locking projection to enter the open recess and coöperate with said locking shoulder.

5. In a linotype machine, the combination of an ejector slide, an ejector blade having a recess open at and extending forwardly from the rear attaching end thereof and provided with a laterally directed notch to

- form a locking shoulder in one of the side walls of the recess, and a pawl connected to the forward end of the slide, said pawl being movable in the plane of said blade and 5 having a hooked end to enter said notch and coöperate with said locking shoulder.
6. In a linotype machine, the combination of an ejector slide having a recessed portion forming a seat at its forward end, an ejector blade having a portion to enter said seat, said portion having a longitudinal recess open at the end thereof and provided with a laterally directed notch forming a locking shoulder in one of its side walls, 10 and a pawl connected to said slide and operative in the plane of the recessed portion thereof, said pawl extending into said recess of the blade and having a laterally directed locking projection to enter said notch and 15 coöperate with said locking shoulder.
7. In a linotype machine, the combination of an ejector slide, an ejector blade provided with a plurality of laterally spaced locking
- recesses open at its attaching end, and a plurality of longitudinally extending pawls 25 connected to said slide, said pawls being movable in the plane of said blade and having similarly arranged locking portions to coöperate with the locking recesses of such blade. 30
8. In a linotype machine, the combination of an ejector slide, an ejector blade, a plurality of pawls movably connected to said slide and coöoperative with said blade to attach it to said slide, and a device for operating said pawls simultaneously to connect and disconnect said blade relatively to said slide and embodying means for locking said pawls in operative position. 35

In testimony whereof I have hereunto set 40 my hand in presence of two subscribing witnesses.

WILLIAM E. BERTRAM.
